US00D924889S

(12) **United States Design Patent** (10) **Patent No.:** **US D924,889 S**
Gromek et al. (45) **Date of Patent:** **** Jul. 13, 2021**

(54) **ELECTRONIC DEVICE WITH GRAPHICAL USER INTERFACE**

(71) Applicant: **Apple Inc.**, Cupertino, CA (US)

(72) Inventors: **Monika E. Gromek**, Oakland, CA (US); **Terry Y. Liu**, San Francisco, CA (US); **Brandon R. Mihai**, San Francisco, CA (US)

(73) Assignee: **Apple Inc.**, Cupertino, CA (US)

(**) Term: **15 Years**

(21) Appl. No.: **29/693,360**

(22) Filed: **Jun. 1, 2019**

(51) LOC (13) Cl. **14-04**

(52) U.S. Cl.

USPC **D14/485**

(58) **Field of Classification Search**

USPC D14/485-495

(57) **CLAIM**

The ornamental design for an electronic device with graphical user interface, as shown and described.

DESCRIPTION

FIG. 1 is a front view of an electronic device having a display screen with graphical user interface applied to the display screen, showing the claimed design; and, FIG. 2 is a front view of an alternative electronic device showing the graphical user interface of FIG. 1 applied thereto.

The broken lines in the figures show an electronic device having a display screen, or an alternative electronic device having a display screen, and form no part of the claimed design.

1 Claim, 2 Drawing Sheets
